UNITED STATES PATENT OFFICE.

DARIUS L. HARSHNER, OF ETNA GREEN, INDIANA.

DESIGN FOR A MEMBER OF A WINDOW-LOCK.

SPECIFICATION forming part of Design No. 33,023, dated July 31, 1900.

Application filed June 28, 1900. Serial No. 21,997. Term of patent 14 years.

To all whom it may concern:

Be it known that I, DARIUS L. HARSHNER, a citizen of the United States, residing at Etna Green, in the county of Kosciusko and State of Indiana, have invented and produced a new and original Design for a Member of a Window-Lock, of which the following is a specification.

This invention relates to a design for a member of a window-lock; and the essential feature resides in a body having upper and lower edges having converging beveled form, a right-angled edge extension at one side, and the opposite side edge indented in V-shaped contour.

The accompanying drawing illustrates a perspective view of a member of a window-lock embodying the features of the design.

The numeral 1 designates a body having upper and lower inwardly beveled or converging edges 2 and 3. The one side edge 4 is indented in V-shaped contour, the body at this point being provided with similarly-shaped bars 5 by the formation of a V-shaped slot 6, having a central transversely-extending curved recess 7, communicating therewith. The opposite side edge is in the form of a right-angled portion 8, with serrations 9 on one surface, and in the body near said portion 8 are outstanding curved tongues 10, which have similarly-formed openings 11 near them.

Having thus described the invention, what is claimed as new is—

The design for a member of a window-lock, herein shown and described.

In testimony that I claim the foregoing as my own I have hereto affixed my signature in the presence of two witnesses.

DARIUS L. HARSHNER.
